United States Patent Office

Des. 189,882
Patented Mar. 14, 1961

189,882

BOWL OR THE LIKE

Leo F. Wildgen, Minneapolis, Minn., assignor to Arthur Salm Inc., Chicago, Ill., a corporation of Illinois

Filed Sept. 12, 1960, Ser. No. 62,097

Claims priority, application Sweden Mar. 22, 1960

Term of patent 14 years

(Cl. D44—15)

Fig. 1 is a perspective view of a bowl showing my new design;

Fig. 2 is a top plan view thereof;

Fig. 3 is a side view thereof;

Fig. 4 is a front view thereof; and

Fig. 5 is a rear view thereof.

I claim:

The ornamental design for a bowl or the like, substantially as shown.
